US00D544882S

(12) **United States Design Patent** (10) **Patent No.:** **US D544,882 S**
(45) **Date of Patent:** **** Jun. 19, 2007**

(54) **AUDIO DATA PLAYER**

(75) Inventor: **Daisuke Kurihara**, Tokyo (JP)

(73) Assignee: **Sony Corporation**, Tokyo (JP)

(**) Term: **14 Years**

(21) Appl. No.: **29/260,323**

(22) Filed: **May 24, 2006**

(30) **Foreign Application Priority Data**

Mar. 1, 2006 (JP) D2006-005022

(51) **LOC (8) Cl.** **14-03**

(52) **U.S. Cl.** **D14/496**

(58) **Field of Classification Search** D14/496,

D14/401, 435, 474, 483, 217, 137, 138, 160,

(57) **CLAIM**

The ornamental design for an audio data player, as shown.

DESCRIPTION

FIG. 1 is a perspective view of an audio data player showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
